CLAIM

The ornamental design for a display panel of a programmed computer system with a graphical user interface, as shown and described.

DESCRIPTION

FIGS. 1, 2, and 3 are first, second, and third views, respectively, of a first embodiment of a display panel of a programmed computer system with a graphical user interface. FIG. 1 is a front view of the first embodiment with the graphical user interface showing a first image in a sequence. FIG. 2 is a second image thereof. FIG. 3 is a third image thereof.

FIGS. 4, 5, and 6 are first, second, and third views, respectively, of a second embodiment of a display panel of a programmed computer system with a graphical user interface.

FIG. 4 is a front view of the second embodiment with the graphical user interface showing a first image in a sequence. FIG. 5 is a second image thereof. FIG. 6 is a third image thereof.

The broken line showing of a portion of a display panel is for the purpose of illustrating environmental structure and forms no part of the claimed design. The broken lines showing of portions of the graphical user interface within the display panel form no part of the claimed design. The appearance of the graphical user interface sequentially transitions between the images shown in FIGS. 1-3 and FIGS. 4-6. The process or period in which one image transitions to another image forms no part of the claimed design.
